UNITED STATES PATENT OFFICE.

WILLIAM J. COOK, OF DENVER, COLORADO.

TRACK INSTRUMENT.

1,372,281.

Specification of Letters Patent. Patented Mar. 22, 1921.

Application filed September 5, 1916, Serial No. 118,523. Renewed February 8, 1921. Serial No. 443,490.

To all whom it may concern:

Be it known that I, WILLIAM J. COOK, a citizen of the United States, and a resident of the city and county of Denver and State 5 of Colorado, have invented certain new and useful Improvements in Track Instruments, of which the following is a full, clear, and exact description, such as will enable others skilled in the art to which the invention ap- 10 pertains to make and use the same.

The invention relates to improvements in track instruments for the purpose of making and breaking an electrical circuit by which train signals are controlled.

15 The invention has for its object the provision of a track instrument for the purpose of making and breaking an electrical circuit to control railway and crossing signals, which said track instrument will not 20 be affected by changes in temperature, or weather conditions in such manner that the same will be rendered inoperative.

Another object of the invention is to provide an electrical circuit make-and-break 25 device adapted to be operated by the action of the railway track under the influence of a passing train.

With these and other objects in view, the invention will now be described with reference 30 to the accompanying drawing, forming a part hereof.

In this drawing, Figure 1 is a plan view of the track instrument, the cover being removed therefrom; Fig. 2 is a longitudinal 35 sectional view of the track instrument taken on the line 2—2 of Fig. 1; Fig. 3 is an elevation view of one of the railway rails, illustrating the application of the track instrument to be operated by the action of 40 the rail; and Fig. 4 is a similar view showing the manner in which the rail is actuated by a passing train.

Corresponding and like parts are referred to in the following description and indicated in all the views of the accompanying drawing by the same reference characters.

Let the numeral 5 represent a housing, formed of metal or other suitable material. This housing 5 is secured to an arm 6 by 50 means of fastening devices 7, the said housing resting upon the said arm 6. The arm 6 extends beyond the housing 5 and receives the base 8 of a rail 9, the outer extremity 55 of the arm 6 being bent over the said base 8 of the rail, and fastening devices 10 secure the arm 6 to the base of the said rail.

An offset 12 is formed in the arm 6, so that the housing 5 will be dropped sufficiently below the head 13 of the rail 9 to prevent the housing from being damaged, 60 or engaged by a passing train. It will be seen that the housing 5 is disposed adjacent the rail 9 at right angles to the latter. A contact bar 14 is pivoted in the housing 5 on a post 15, as shown at 16, one extremity 65 of said contact bar 14 extending beyond the housing 5 through an opening 17 in the end of the housing adjacent the rail 9 and engages with one end of an operating lever 18. This operating lever 18 extends parallel with 70 the rail 9 and is pivoted intermediate its extremities to the said rail, as shown at 20, one end of said operating lever being also pivoted to the said rail, as shown at 21. This operating lever is bent intermediate 75 its extremities to provide for the leverage, the purpose of which will later appear. Spaced apart contact members of an electrical circuit 22 are arranged in the housing 5 at one end of the latter, the said contact members being designated 23 and 24. The inner end of the contact bar 14 is provided with a transverse member 25, which is adapted to bridge the space between the contacts 23 and 24 for closing the said electrical circuit 22. 80 85

While a train is passing over the track, the rails 9 are caused to bend, as represented in Fig. 4. The numeral 26 in this figure represents a wheel of a train. Now, 90 as the train 26 engages the rail 9, the latter is caused to bend and as a consequence actuates the operating lever 18 on its fulcrum. This operating lever 18 being engaged with the outer extremity of the contact bar 14, 95 will cause the latter to be actuated and disengage the transverse member 25 from the contacts 23 and 24, thereby breaking the electrical circuit 22. Now, when the train has passed the pivotal point 20 of the operating lever 18, the latter will assume its normal position, and the contact bar 14 will be actuated back to its circuit closing position with the transverse member 25 in engagement with the contacts 23 and 24. The contact bar 14 is provided with a weight 27 on 100 one side of the pivotal point 16 thereof, which said weight causes the contact bar 14 to positively and instantly actuate the transverse member 25 from engagement with the 110 contacts 23 and 24. The weight of the operating lever 18 in moving back to its nor-

mal position will actuate the contact bar 14 back to its circuit closing position against the influence of the weight 27. A spring 28 insures the contact bar 14 moving to its 5 circuit closing position in case the weight of the operating lever 18 fails to return said contact bar.

It will be understood that railway signals are, as a rule, operated on either the closed 10 circuit principle or the open circuit principle. This invention may, by suitable minor variations in construction, be employed in either connection.

The outer extremity of the contact bar 14 15 is received in a bifurcation in one extremity of the operating lever 18, as shown at 29.

From the foregoing description, it will be seen that this invention is designed to be applied to and operated by the action of the 20 rails of the railway track under the influence of the downward movement of the rails when a train is passing over the same. The fact that the entire mechanism is attached to and carried by the rails obviates 25 inconsistent expansion and contraction under the influence of weather conditions. But, on the other hand, the various instrumentalities, or elements of the track instrument will expand and contract in unison 30 with the rails, thereby maintaining constantly, under any conditions, their relative positions, and, as a consequence, insuring positive and efficient operation at all times.

While I have described and illustrated 35 herein a specific form of my invention, it is understood that I am not limited thereto and that the invention may be modified and varied without departing from the spirit of the same, or the scope of the appended 40 claims.

Having thus described my invention, what I claim and desire to secure by Letters Patent is:—

1. A circuit make-and-break device for 45 railway signals, consisting of a housing secured to one of the rails of the railway track, circuit contacts positioned within said housing, a contact bar fulcrumed in said housing and having one extremity protruding 50 therefrom, said contact bar being dis-

posed at right angles to said rail, an operating lever having one extremity set at an angle, said operating lever being disposed longitudinally with said rail and pivoted intermediate its extremities in the corner of 55 said angle to said rail, the extremity of said operating lever set at an angle extending upwardly and engaged with said rail, and the other extremity of said operating lever engaging said protruding extremity of said 60 contact bar.

2. A circuit make-and-break device for railway signals, comprising a contact bar pivotally mounted, an operating lever having one extremity set at an angle, said operating lever extending longitudinally with 65 said rail and pivoted intermediate its extremities to said rail in the corner of said angle, the extremity of said operating lever set at an angle extending upwardly and engaged with said rail immediately below the head of the latter, and the other extremity 70 of said operating lever engaging said contact bar.

3. A circuit make-and-break device for 75 railway signals, consisting of a housing secured to one of the rails of the railway track, circuit contacts positioned within said housing, a contact bar fulcrumed in said housing and having one extremity protruding 80 therefrom, said contact bar being disposed at right angles to said rail, an operating lever extending longitudinally with said rail and pivoted intermediate its extremities to said rail, one extremity of said 85 operating lever being extended upwardly and engaged with said rail immediately under the head of the latter, the other extremity of said operating lever having a bifurcation therein receiving the protruding 90 extremity of said contact bar, and said contact bar having a weighted part intermediate the point of its fulcrum and said circuit contacts.

In testimony whereof, I affix my signature 95 in the presence of two witnesses.

WILLIAM J. COOK.
